(57) **CLAIM**

The ornamental design for a “facial cleansing brush with base,” as shown and described.

DESCRIPTION

FIG. 1 is a perspective view of a facial cleansing brush that shows the facial cleaning brush in the base; FIG. 2 is a front view thereof; FIG. 3 is a rear view thereof; FIG. 4 is a left side view thereof; FIG. 5 is a right side view thereof; FIG. 6 is a top view thereof; and FIG. 7 is a bottom view thereof; FIG. 8 is perspective view of the base of the facial cleansing brush, shown separately for clarity of illustration; FIG. 9 is a front view thereof; FIG. 10 is a rear view thereof; FIG. 11 is a left side view thereof; FIG. 12 is a right side view thereof; FIG. 13 is a top view thereof; and FIG. 14 is a bottom view thereof; FIG. 15 is a perspective view of a head of the facial cleansing brush; FIG. 16 is a front view thereof; FIG. 17 is a rear view thereof; FIG. 18 is a left side view thereof; FIG. 19 is a right side view thereof; FIG. 20 is a top view thereof; and FIG. 21 is a bottom view thereof; FIG. 22 is an enlarged partial view “22” in FIG. 8, shown separately for ease of illustration; FIG. 23 is an enlarged partial view “23” showing the brush head in FIG. 9; FIG. 24 is an enlarged partial view “24” showing the brush head in FIG. 10; FIG. 25 is an enlarged partial view “25” showing the brush head in FIG. 11; FIG. 26 is an enlarged partial view “26” showing the brush head in FIG. 13; and, FIG. 27 is an enlarged partial view “27” showing the brush head in FIG. 15. The base shown in FIGS. 8-14 and the brush head shown in FIGS. 15-21 are shown separately for clarity of illustration. The broken lines in the figures depict portions of the facial cleansing brush with base that form no part of the claimed design.
